UNITED STATES PATENT OFFICE.

ROBERT S. LAWRENCE, OF WASHINGTON, DISTRICT OF COLUMBIA.

CARBURETOR.

SPECIFICATION forming part of Letters Patent No. 340,221, dated April 20, 1886.

Application filed December 2, 1885. Serial No. 184,385. (No model.)

To all whom it may concern:

Be it known that I, ROBERT S. LAWRENCE, a citizen of the United States, residing at Washington, in the District of Columbia, have 5 invented certain new and useful Improvements in Carburetors; and I do hereby declare the following to be a full, clear, and exact description of the invention, such as will enable others skilled in the art to which it appertains to 10 make and use the same.

My invention relates to certain new and valuable improvements in carburetors; and it has for its objects to provide means for delivering oil from the reservoir to a distributing-pan in the tank in such a manner as to insure 15 an even flow of the oil over the bottom of the pan; to provide for a thorough distribution of the oil by means of an improved system of distributing-pans; to provide a central support 20 for the pans and distributing and gathering pipes by placing the float-well in the center of the tank; to provide for an even distribution of the air or gas to be carbureted to the packing in the tank; to provide many exits 25 for the carbureted air or gas by means of a series of concentrically - arranged perforated gathering-pipes, whereby the air or gas is made to pass through the packing in all parts 30 of the tank, whereas if there were but a single exit it would all pass in one line to that exit; to avoid inconvenience resulting from the rapid evaporation of the oil in the tank by providing a series of concentrically-arranged 35 perforated gathering - pipes and connecting them independently with the outlet-pipe, and to enable the operator to readily ascertain the quantity of oil in the reservoir, and at the same time prevent the escape of odor from the oil by the combination, with the reservoir, of 40 a water-sealed gage.

Referring to the accompanying drawings, Figure 1 is a vertical section of the carburetor, taken through the center. Fig. 2 is a perspective view of the branch pipe. Fig. 3 is a 45 front elevation of the inlet and outlet pipes and the cross-pipe connecting them, each provided with a stop-cock. Fig. 4 is a plan view of the series of gathering-pipes and their braces or supports. Figs. 5, 6, and 7 are plan 50 views of the distributing pans. Fig. 8 is a plan view of the series of distributing-pipes,

each provided with a wire-gauze covering. Figs. 9 and 10 are detail views.

A represents a tank, made of copper or other suitable metal, and preferably square in 55 shape. This tank, as well as the distributing-pans hereinafter mentioned, are packed with a finely-prepared packing of absorbent material, as excelsior.

On top of tank A is mounted a reservoir, B, 60 of greater superficial area than the tank, for containing hydrocarbon or other suitable oil. Oil is let into the reservoir through one of two stop-cocks, b, on top, the other cock serving 65 as a vent for the gas, which may be conducted back into the barrel by a hose inserted in the bung.

It is very desirable to be able to ascertain at any time how much oil there is in the reservoir, and for this purpose I have attached 7c thereto a fluid-gage, U, (seen in Fig. 1,) which is a glass tube, the ends of which are inserted in screw-threaded metal connections u, after the manner of the ordinary steam-boiler gage. In order to prevent the escape at the joints of 75 odor from the oil, I water-seal the gage, the seal-casing U' being of metal with a glass plate, u', in front, an inlet-cock, u², on top, and an outlet-cock, u³, at the bottom. The casing being filled with water, in order to ascertain the 80 quantity of oil in the reservoir, it is only necessary to draw off the water to the level of oil in the gage, when the casing may be immediately refilled.

On top of the reservoir is a chamber, C, to 85 be filled with water for sealing the stop-cocks b, and also the hood, hereinafter mentioned, in order to prevent the escape of odor, the chamber being provided with a hinged lid, c, and a draw-off pipe, c'. Extending centrally from 9c the top of the reservoir to the bottom of the tank is a float-well, D, perforated near its bottom, as at d, which perforations are covered by a wire screen, d'.

In reservoir B, at one side of the float-well, 95 is a valve-chamber, E, which extends from the top of the reservoir to the bottom thereof, the chamber being perforated at its lower end, as at e.

F represents a hood provided with a screw-cap, f, on top of the reservoir and within the water-chamber C. This hood covers the up-

per ends of the float-well and valve-chamber, and also gives space for the free working of the upper portion of the valve-operating mechanism.

5 G represents a float in well D, to which float is connected one end of a rod, g, the other end of said rod being connected to one end of a lever, h, pivoted in a standard, H, rising from the top of the reservoir. To the other end 10 of lever h there is pivoted one end of a jointed rod, i, the other end of which rod is attached to the valve I in valve-chamber E. The valve-chamber is suitably packed, as at i', to prevent upward flow of the fluid.

15 J represents a branch pipe, whose upper end passes through the bottom of the reservoir and communicates with the valve chamber, and whose lower branched ends (best seen in Fig. 2) pass on either side of the float-well and lead 20 into the upper distributing-pan, presently to be described.

K, L, and M represent a series of distributing-pans, which are clearly illustrated in Figs. 5, 6, and 7. These pans are each formed with 25 a square opening in the center of a size just sufficient to fit neatly over the float-well, and they are placed thereon and attached thereto in the order named. Besides being attached to the well, the pans L and M are also attached 30 at their outer edges to the sides of tank A.

Pan K is perforated at each corner, as shown at k in Fig. 5, and in order to prevent the oil from being carried along the bottoms of the pans by capillary attraction, and thus unduly 35 concentrating at certain points, all the pans are provided on their under sides at their outer edges with a drip-wire, l, soldered thereto, as shown in Fig. 10, which figure represents so much only of one of the pans—say of 40 pan K—as is necessary to illustrate this feature.

N N' N² represent a series of concentrically-arranged gathering-pipes supported close up against the bottom of the reservoir by braces 45 n, whose inner ends are attached to a square frame, n', which fits over and is attached to the float-well, and whose outer ends are attached to the tank. It will be seen that these pipes, as thus arranged, give a good support to that 50 portion of the bottom of reservoir B which overlies tank A.

As will be seen on referring to Fig. 4, the pipes of the gathering system are of different diameters, the outer one being the larger and 55 the inner one the smaller. These gathering-pipes are perforated on the lower side and are independently connected with an outlet-pipe, O, by means of connecting-pipes P P' P², as clearly shown in Fig. 1. In the under side of 60 pipe O there is a slot, o, for a purpose herein-after stated.

Beneath the system of gathering and connecting pipes there is a wire screen, Q, (shown in dotted lines, Fig. 1,) secured to the sides of 65 the tank and to the float-well.

R R' R² represent a series of distributing-pipes placed close up under and aiding in

supporting the bottom of the lower distributing-pan, M. These pipes are arranged and supported in a manner similar to the arrangement and support of the gathering-pipes, as seen in Figs. 1 and 8; but instead of each having an independent connection with an inlet-pipe, S, like the connections of the gathering-pipes with the outlet-pipe O, they communicate with each other by means of connecting-pipes r r', and the larger pipe, R, alone is connected with the inlet-pipe, as at r². The pipes of this series are perforated on both the front and rear sides, and these perforations increase 80 in size in both directions from their points of connection. A wire-gauze covering surrounds these pipes, as shown in dotted lines in Fig. 8, to prevent the perforations getting clogged up. 85

For convenience of connection with the distributing-pipes that part of inlet-pipe S which is inside the tank is diagonally arranged, as shown in Fig. 9.

The inlet and outlet pipes pass through the 90 tank in the same plane, and on the outside of the machine these pipes are connected by a cross-pipe, T, each of said pipes being provided with a stop-cock, as 1 2 3.

Having now described the construction of 95 my machine, I will proceed to explain its operation.

The reservoir being filled with hydrocarbon oil, the oil will flow through the perforations in the valve chamber into the branch pipe J, 100 and by that pipe be conveyed to the pan K on two opposite sides of the float-well, in order that there may be an equal distribution of the oil to the four corners of said pan. From pan K the oil will flow through perforations k into pan L, and after filling this pan will flow over into the packing beneath. When the packing under pan L has become thoroughly saturated the oil will be caught by pan M until it fills, and will then overflow into the packing in the 110 bottom of the tank. By this system of distribution the packing in the pans and tank becomes thoroughly and uniformly saturated. When a sufficient quantity of oil has accumulated in the bottom of the tank to raise the 115 float, the valve will automatically cut off the supply until there has been sufficient evaporation of the oil to allow the float to descend, when the valve will again open and admit a 120 fresh supply. The air or gas to be carbureted is admitted under pressure through inlet-pipe S to the series of distributing-pipes R R' R², and is forced therefrom through the perforations into the interior of the tank, and, owing to the fact that the perforations in these pipes 125 at points distant from the entrance of the connecting-pipes are larger than those in that immediate vicinity where the pressure is greater, a comparatively even distribution of the air or gas is obtained.

On leaving the distributing-pipes the air or gas permeates the saturated packing, and, rising to the top of the tank, takes up carbon from the oil, and thus becomes thoroughly carbureted, this latter re- 130

sult being due to the fact that the system of perforated gathering-pipes, covering nearly the entire surface of the upper portion of the tank, offers numerous exits to the air or gas, and therefore it is not drawn over a single line, as it would be were there but a single exit. On reaching the top of the tank the carbureted air or gas is taken up by the gathering-pipes and delivered to the outlet-pipe to be conveyed away for use.

Owing to the rapid evaporation of the oil, the perforations in one of the gathering-pipes might possibly freeze up, and thus temporarily fail to deliver air or gas; but inconvenience from that source is entirely avoided by the independent connection of the gathering-pipes with the outlet-pipe, for by this construction, if either one of those pipes should for a time become useless, an abundant supply of air or gas would be delivered by the other two. Again, inconvenience would be liable to result from the deposition of residuum in the outlet-pipe, as the residuum, if allowed to accumulate, would eventually close the pipe and shut off the supply of carbureted air or gas. This liability, however, is avoided by the slot in the under side of the pipe, through which the residuum will drop into the tank. Should there be an accumulation of residuum in the bottom of the tank, it can be readily removed by a pump inserted in the well, the float having first been taken out, thus dispensing with the objectionable use of cocks in the side of the tank.

If at any time it should be desirable to use gas without passing it through the carburetor or disturbing the connections, this can be done by opening stop-cock 3 in the cross-pipe T and closing cocks 1 and 2 in the inlet and outlet pipes.

Having thus described my invention, what I claim as new, and desire to secure by Letters Patent, is—

1. The combination, with the tank of a carburetor, of a series of concentrically-arranged perforated distributing-pipes, one of said pipes being connected with the inlet-pipe, and all the pipes of the series connected with each other, substantially as described.

2. The combination, with the tank of a carburetor, of a series of concentrically-arranged perforated distributing-pipes, the perforations

in the vicinity of the pipe-connections being smaller than those at a distance therefrom, substantially as described, and for the purpose set forth.

3. In a carburetor, the combination, with the tank, a float-well located in the center of the tank, and a distributing-pan secured at its center to the well and at its outer edges to the tank, of a series of concentrically-arranged distributing-pipes located close up under the bottom of said pan and giving support thereto, the pipes being attached at the center to the well and resting on braces, which are also attached to the well and to the tank, substantially as described.

4. In a carburetor, the combination, with the tank, of an outlet-pipe and a series of concentrically-arranged perforated gathering-pipes connected therewith, for the purpose set forth.

5. In a carburetor, the combination, with the tank, of an outlet-pipe and a series of concentrically-arranged perforated gathering-pipes independently connected with the outlet-pipe, in the manner and for the purpose substantially as set forth.

6. In a carburetor, the combination, with a tank, an oil-reservoir on top of the tank, and a float-well located in the center of the tank and reservoir, of a series of concentrically-arranged gathering-pipes at the top of the tank and against the bottom of the reservoir, said pipes receiving partial support from the well, to which they are attached at the center, and being further supported by braces attached to the well and to the tank, in the manner described, and for the purpose set forth.

7. The combination, with an oil-tank, of a water-sealed gage, substantially as described, and for the purpose set forth.

8. The combination, with an oil-tank, of a glass water-sealed gage, the casing for holding the water that seals the gage being provided with a glass front and an inlet-cock and an outlet-cock, substantially as described, and for the purpose set forth.

In testimony whereof I affix my signature in presence of two witnesses.

ROBERT S. LAWRENCE.
